SPRING HYDRAULIC MOTOR FOR PRESSURE RECORDING BOMBS

Horace Vivian Steadman, Dallas, Tex., assignor to Shell Development Company, San Francisco, Calif., a corporation of Delaware

Application April 21, 1934, Serial No. 721,670

4 Claims. (Cl. 185—37)

This invention pertains to pressure recording gauges, particularly such as are used to measure pressure in wells, and has for its purpose to provide an improved spring hydraulic motor for the 5 operation of such gauges.

It is known in the art to record the pressure in wells by means of bombs lowered therein, and containing a strip of paper on which a stylus, connected to a helical tube of the Bourdon type 10 communicable with the well, traces a line representing the well pressure, while another device, such as an electrical motor or a clock mechanism, actuates the paper strip at a uniform rate, thus introducing the time element in the well-pressure graph.

Such devices, however, being of a more or less complex construction, are not always reliable in operation under the hard conditions of wear and tear prevailing in deep well pressure measurements, and it is a purpose of this invention to 20 replace them with a spring hydraulic motor of rugged construction and having a small number of simple and easily adjustable parts.

Further objects and advantages of the invention will become apparent from a consideration 25 of the following description taken in connection with the accompanying drawings.

In the drawings, Figs. 1, 2, 3 and 4 are vertical views, partly in cross-section, of four different embodiments of the spring hydraulic 30 motor.

Fig. 5 is a horizontal cross-sectional view of the device taken along line A—A of Fig. 1.

Figs. 6 and 7 are horizontal cross-sectional 35 views of the device taken respectively along lines A—A and B—B of Fig. 2.

Figs. 8, 9 and 10 are horizontal cross-sectional 40 views of the device shown on Fig. 4.

Figs. 11 and 12 are horizontal cross-sectional 45 views of the device shown on Fig. 3.

However, the applicant does not wish to limit himself to these particular types of construction, and may use any other embodiment to carry his 50 invention into practice while retaining the same principle of operation.

This principle consists in using a single or a multiple spring as a power-source, driving a piston through a cylinder completely filled with a more or less viscous liquid, the speed of the piston 55 being regulated by the rate at which the liquid passes from one side of the piston within the cylinder to the other. This may be controlled in a number of different ways. For example, a fixed orifice may be mounted in the piston head; a groove of constant or varying cross-section

may be cut in the wall of the cylinder; an orifice may be cut in the piston head so as to move over a central mandrel of constant or varying cross-section, or a groove of constant or varying cross-section may be cut in the central mandrel. 5 All these different ways will be discussed later.

All motors, illustrated in Figs. 1, 2, 3 and 4, consist of an outer shell 1, closed by an upper head 2 and a lower head 3 screwed onto the threaded ends of the cylinder. The lower head 10 carries a stuffing box fitted with a gland piece 4 and a gland nut 5 through which passes a piston rod 6.

Referring specifically to Fig. 1, there is shown within the cylinder and mounted on a piston 15 rod 6, a piston 7 having an orifice nozzle 8, which is interchangeable and may be given any desired size, and a check valve 9. Above the piston is mounted a spring 10 seated against the upper cylinder head and piston respectively. 20

All free space above and below the piston is filled with a suitable liquid. In preparing the motor for use, the piston is forced for example, manually towards the upper end of the cylinder until the spring is fully compressed. In this 25 operation the liquid trapped above the piston forces open the check valve against its spring and passes through to the under side of the piston. On release, the spring forces the piston downwards and, as the check valve has automatically closed, the liquid can return to the upper side of the piston only through the orifice in the nozzle. This latter, therefore controls the rate of flow in accordance with the pressure exerted by the spring and the viscosity and temperature of the fluid, and, consequently, controls 30 also the rate at which the piston moves downwards.

Another way in which the spring-hydraulic motor may be constructed is shown in Fig. 2, 40 and is identical to that of Fig. 1, with the exception that no orifice nozzle is provided in the piston-head. In place of this there is cut in the cylinder wall a shallow groove 11. This groove may be parallel-sided and of constant 45 depth, parallel sided but of varying depth; of constant depth but with tapered sides, or in fact of any combination of depth and form of outline necessary to provide a constant or variable speed of travel of the piston and rod. 50

The operation of the motor in this case is similar to that discussed above, with the exception that the liquid passes from the under to the upper side of the piston between the side of the piston and the wall of the cylinder through the 55

space provided by the groove in the cylinder wall.

Still another way of constructing the motor is shown in Fig. 3, where the upper part of the piston rod 12 is of hollow or tubular construction and the lower part 6 solid. In the upper end of the hollow portion are provided perforations 15 to allow the fluid to pass between the cylinder and the inner space of the piston-rod. Attached 10 to the upper cylinder head by a cap screw 14 is a mandrel 16. This may be parallel sided or tapered to any desired profile. Through the center of the mandrel is a passage 20 communicating with a chamber in which is mounted a 15 check valve 9 seated against the passage through the cap screw 14 communicating through ports 17 in the walls of the mandrel with the space above the piston.

In operation, when the piston is forced up- 20 wards, compressing the spring, the liquid above the piston passes through the ports 17 in the top of the mandrel, to the passages in the cap screw, thence through the check valve 9 and the mandrel central passage 20 into the hollow piston 25 rod, through the ports 15 therein and out into the cylinder beneath the piston.

On the spring forcing the piston down, the fluid passes to the top of the piston through the ports 15, the annular space 18 between the outer sur- 30 face of the mandrel and the opening through which the mandrel projects. By varying the contour of the mandrel 16 the escape of the fluid and the movement of the piston 7 and rod 6 may be made constant.

35 Fig. 4 shows a motor constructed similarly with the one just described, with the exception that the mandrel 16' is cylindrical and has in it a groove or a cut-away portion 19. This may be cut parallel to the axis of the mandrel or at an angle to it to provide either a constant or a progressively varying orifice for the passage of the fluid between the opening through the piston and the surface of the mandrel.

40 A motor of any of the described types of construction may be mounted in a pressure-recording bomb, wherein the end of the piston rod 6 is attached to a vertically movable chart carrier, with a stylus or pen connected to the closed end of a Bourdon tube bearing against the chart.

45 The operation of the bore hole pressures recording bomb is as follows. With the vertical movement of the chart transmitted from the motor by the piston rod 6 and the radial horizontal movement of the pen under increasing pressure 50 within the Bourdon tube, there will be drawn on the chart a line which, when the chart is removed and laid out flat, will be diagonal to the side and bottom of the chart sheet. As the instrument is calibrated and the movement of the pen for each pound increment in pressure is known, a measurement of the amount of movement that has taken place will indicate the well 55 pressure.

I claim as my invention:

1. In a well-pressure recording bomb, a piston rod for attaching a chart carrier, a spring hydraulic motor consisting of a hollow cylinder substantially filled with a liquid, a cylinder head, 5 a piston rigidly connected to said piston rod, a spring braced against the cylinder head, and the piston, and means for producing a constant flow of the liquid from one side of the piston to the other when the piston is caused to move in the 10 cylinder by the action of the spring.

2. The apparatus of claim 1, wherein the means for controlling the flow of the liquid from one side of the piston to the other consists of a groove of increasing cross-section cut in the 15 cylinder wall to allow the flow of the liquid when the piston is caused to move through the cylinder by the action of the spring.

3. In a well-pressure recording bomb, a hollow piston rod for attaching a chart-carrier, a pis- 20 ton head attached to said piston rod, a spring-hydraulic motor comprising a hollow cylinder substantially filled with a liquid, a cylinder head, 25 a spring braced against the cylinder-head and the piston-head, and means to control the flow 30 of the liquid from one side of the piston to the other when the piston is caused to move through the cylinder by the action of the spring, said means comprising a mandrel of varying cross- 35 section attached to the cylinder head, a central passage in said mandrel, an orifice in the piston head leaving an annular opening around the mandrel, a check valve and perforations in the upper part of said mandrel communicating with the cylinder space above the piston, and perforations in the walls of the hollow piston-rod communicating with the cylinder space below the piston.

4. In a well-pressure recording bomb, a hollow piston rod for attaching a chart-carrier, a piston head attached to said piston rod, a spring-hy- 40draulic motor comprising a hollow cylinder sub-stantially filled with a liquid, a cylinder head, a spring braced against the cylinder-head and the piston-head, and means to control the flow 45 of the liquid from one side of the piston to the other when the piston is caused to move through the cylinder by the action of the spring, said means comprising a mandrel of constant cross-section having a groove of varying cross- 50 section cut in it attached to the cylinder head, a central passage in said mandrel, an orifice in the piston head leaving an annular opening around the mandrel, a check valve and perforations in the upper part of said mandrel com- 55municating with the cylinder space above the piston, and perforations in the walls of the hollow piston-rod communicating with the cylinder space below the piston.

HORACE VIVIAN STEADMAN.
